UNITED STATES PATENT OFFICE.

CHARLES A. BAILEY, OF CROMWELL, CONNECTICUT.

CARTRIDGE.

SPECIFICATION forming part of Letters Patent No. 674,751, dated May 21, 1901.

Application filed March 5, 1901. Serial No. 49,805. (No model.)

To all whom it may concern:

Be it known that I, CHARLES A. BAILEY, a citizen of the United States, and a resident of Cromwell, in the county of Middlesex and State of Connecticut, have invented a Cartridge, of which the following is a specification.

This invention is an improvement upon the cartridges shown and described in my prior 10 patents, Nos. 640,855 and 640,856, issued January 9, 1900, the object of the present invention being to provide an improved breech-piece and anvil, the said anvil being securely held in the nipple of the breech-piece, with 15 spaces left at each side, through which the flame of the fulminate may pass to the powder charge of the cartridge.

With the above object in view the invention consists in forming the nipple of the 20 breech-piece with a bead or shoulder at its inner end adapted to securely hold the anvil in said nipple, combined with the paper tube crimped so as to fit over the breech-piece and be engaged thereby when the parts are inserted in the metal cap.

In the following specification I have entered into a detail description of my invention, reference being had to the accompanying drawings, and to letters of reference 30 thereon, which designate the different parts, and what I claim as new is more specifically set forth in the appended claims.

In the drawings forming a part hereof, and in which like letters of reference indicate like parts, Figure 1 is a sectional view of a cartridge constructed in accordance with my invention. Fig. 2 is a sectional view of the breech-piece and anvil prior to the compression of the retaining-bead. Fig. 3 is a similar view showing the retaining-bead compressed. Fig. 4 is a detail view of the anvil.

Fig. 5 is a view illustrating a modification of the invention. Fig. 6 is a view showing the anvil of Fig. 5.

Referring to Figs. 1, 2, 3, and 4, A designates the breech-piece, which is stamped from sheet metal to present an inwardly-projecting annular flange *a* and an outwardly-projecting straight central portion or nipple *A'*. In this nipple is placed a cup-shaped anvil 50 *B*, having its central portion stamped or struck to present an inwardly-projecting

point *b*, upon which the fulminate is placed, the said point being below the ends of the side pieces of the anvil. After the anvil is 55 inserted in the nipple of the breech-piece a bead *a'* is pressed or rolled at the inner end of said nipple and compressed, as shown in Fig. 3, thereby to retain the anvil in place, reinforce the inner end of the nipple, and 60 form a strong shoulder for the abutment of the anvil. This construction forms a breech-piece embodying an effective primer and adapted to be used in combination with the crimped paper tube *C* and metal cap *D*, the 65 connection of the parts forming the complete cartridge being such that the destructible paper tube and breech-piece can be removed from the metal cap and said cap used over again.

In assembling the parts the breech-piece is inserted in the paper tube with the nipple projecting through the central opening at the crimped end thereof. These parts are then inserted into the metal cap and the nipple 75 fitted into the tapered opening *d* in the head of said cap, after which the cartridge-shell so formed is operated upon in a suitable die to press the inner part of the breech-piece into the tube and expand the outer portion of the 80 nipple into the tapered opening in the cap, thereby firmly connecting the several parts together to form a cartridge-shell primed and ready to receive the charge.

By placing the fulminate upon the inner 85 side of the anvil instead of upon the inner side of the end wall of the nipple it will not be disturbed when said nipple is upset or expanded in clamping the parts in the metal cap. The construction herein shown and described 90 forms a very effective priming device for the breech-piece, and in forming a new cartridge it is only necessary to purchase the breech-piece and crimped tube, as the metal cap itself will not be injured and can be used a 95 number of times. The flange *a* of the breech-piece may extend up in the shell a distance equal to the space occupied by the powder charge and will reinforce the paper tube and sleeve of the metal cap.

In the modification illustrated in Figs. 5 and 6 the inner end of the nipple *E* is enlarged to form a shoulder *c*, upon which the ends of an anvil or bent plate *F* rest, a bead *f* being

formed above the end of the anvil and compressed thereon to securely connect the parts and form a rigid support for the anvil. The central portion of the anvil is punched to form 5 a point f' , against which the fulminate contacts in exploding the same. In this style of breech-piece the end of the nipple may be formed with threads for connecting it to a metal cap having a threaded opening.

10 It will be understood that the inner end of the paper tube may be plain instead of crimped and will be held by the annular flange of the breech-piece.

Having thus described my invention, what 15 I claim as new, and desire to secure by Letters Patent, is—

1. In a cartridge, the combination with the metal cap having an opening, of a breech-piece stamped of sheet metal to form a reinforcing-flange and a projecting nipple, a U- 20 shaped anvil located therein and having the

fulminate on the inner side thereof, and a bead pressed into the inner end of the nipple above the anvil; together with the paper tube held in place by the breech-piece, the parts 25 being assembled, substantially as shown and described.

2. In a cartridge, the combination with the metal cap having an opening therein, of a breech-piece stamped from sheet metal to form 30 a reinforcing-flange and projecting nipple, a U-shaped anvil located therein, a point projecting from the inner side of said anvil, the fulminate being placed within the U-shaped anvil; together with the paper tube held in 35 place by the breech-piece, the parts forming the cartridge being assembled, as herein shown and described.

CHAS. A. BAILEY.

In presence of—

JOSEPH ZEISER,

ARTHUR BOARDMAN.
